SUBMARINE BARRIER

Giovanni Emanuele Elia, Rome, Italy

Application September 11, 1933, Serial No. 689,030
In Switzerland September 29, 1932

4 Claims. (Cl. 102—3)

The present invention relates to submarine barriers which are used as defense against all types of floating war craft, ships moving on the surface of the water and submarines.

5 The principal object of the invention is the provision of a submarine barrier comprising interconnected buoys having means of defense, for example an explosive charge or sounding means, so that a ship running against the barrier may be 10 either destroyed or will have its position signaled by the sounding buoys.

Another object is the provision of an electric circuit for each buoy having defense means and which circuit includes a device responsive to 15 a current flowing through the circuit to release the defense means in the buoys.

A further object is to provide metal such as 20 copper along the means interconnecting the buoys and including such metal in the above referred circuit including also the metal wall of a buoy, so that a ship running into the barrier and its steel hull is making contact with said metal and with the wall of a buoy, an electric cell is constituted by the steel hull of the ship, 25 said metal and the sea water, which cell feeds the above referred circuit to operate the defense means in the buoys.

Another object is the provision of a submarine barrier which comprises anchored floating buoys 30 between which are disposed the interconnected buoys containing an explosive charge or sounding means.

A still further object is the provision of a submarine barrier which may be placed as a whole 35 into the sea and wherein said floating buoys comprise devices for automatically releasing anchoring means when the barrier has reached a predetermined depth.

With the above and other objects in view, my 40 invention consists in the features of construction and operation set forth in the following specification and drawings, in which,

45 Figure 1 is a general view of a first form of embodiment of a submarine barrier according to the invention.

Figure 2 is a diagrammatic and sectional view of a buoy comprising an explosive charge.

Figure 3 shows a buoy comprising sounding means.

50 Figure 4 shows the barrier in operation after a ship has run into it.

Figure 5 illustrates the manner in which a barrier will be removed.

55 Figure 6 illustrates a further form of embodiment of the barrier.

Figure 7 shows one of the floating buoys of this barrier.

Figure 8 shows a third form of a barrier while being placed into the sea.

Figure 9 shows this barrier after being anchored at sea.

Figure 10 shows a detail part.

In the barrier according to Figure 1 two concrete blocks or foundations 1 are resting on the bottom of the sea A. To each block is attached 10 a cable 2 connected to a floating buoy 3 and each buoy carries a cable or chain 4a to which is attached a pulley 4. A cable 7 passes over the pulleys 4 and has either of its ends connected to an explosive buoy 6, the two buoys 6 being connected to each other by means of a copper or other metal cable 5. The cable 7 carries a pulley 9 to which is attached an explosive buoy 8 and which is connected by a cable 10 to the cable 5. The buoyancy of the buoy 8 is different from that 15 of the buoys 6 so that the loop formed by the cables 5 and 7 and buoys 6 is held extended in a substantially vertical plane by the buoy 8 bearing on the cable 7.

The three explosive buoys 6 and 8 are identical 20 and one of them is represented in Figure 2. It comprises an explosive charge 11 which can be made to explode by means of two time fuzes 12 and 13. The fuze 13 may be actuated by a mechanical device 14 of any known type placed 25 under the control of the cable 7 to be put in action upon the cable being subjected to an excessive tension. The fuze 12 is put in action when an electric circuit, in which is included the fuze and the source of current 15, is closed. This 30 circuit comprises two interrupters of which the first one is composed of the two fixed contacts 16 and 17 which can be bridged by a mobile contact 18 constituted by the moving magnet of a galvanometer. The second interrupter 35 comprises the two contacts 19 and 20 which may be bridged by the contact 20a controlled by a device 20b of known type comprising an elastic diaphragm subjected to the static pressure of the sea water.

The winding of the galvanometer 18a is connected by an insulated conductor 21 to the copper cable 5 and by the conductor 22 to a contact 23 which can be connected to the contact 24 by a movable contact 25 which is also actuated by 45 the above referred device 20b. The contact 24 is connected to the wall 27 of the buoy which is conducting and may be made of brass for instance. The two interrupters constituted by the contacts 19, 20 and 20a on the one hand, and 23, 50 55

24 and 25 on the other hand, are closed by the action of the device 20b when the buoys 6 and 8 are placed at the required depth into the sea.

When a war ship, as for example a submarine 5 B runs into the barrier, the bow of the ship will catch the cable 5 (Fig. 4) and the barrier will be broken. Preferably the cable 7 will be made weaker than the cable 5 so that the cable 7 is cut. Owing to the movement of the ship, the buoys 6 and 10 8 close together towards the hull of the ship. As soon as the iron hull makes contact with the wall 27 of an explosive buoy, a current will pass through the winding of the galvanometer 18a because the iron of the ship, the sea water and 15 the copper of the cable 5 constitute an electric cell which is connected to the galvanometer, and the interrupters 19 and 20 are maintained closed by the pressure of the sea water. The magnet 18 thus connects the contacts 16 and 17 and the 20 source of electricity 15 operates the fuze 12 which ignites the explosive charge after the time for which it had been set.

If the war ship would be provided with shears for cutting the cables of the barrier, the galvanometer of the buoys would be actuated in the same manner as before as soon as it would be tried to cut the cables; the electric cell would be constituted by the steel of the shears, the sea water and the copper cable.

30 If for any reason the fuze 12 would not be actuated when a ship runs into the barrier, the fuze 13 would become operative when the cable 5 becomes overtensioned by the action of the ship.

In the place of explosive buoys 6 and 8 there 35 could be used sounding buoys. Such buoys would also contain a galvanometer, a source of current and a relay but the explosive charge would be replaced by a sounding device of any known type or by a radio transmitter which would be operated when the relay is closed. It is also possible to use buoys giving light signals when a war ship runs into the barrier. The source of current 40 and the galvanometer with the interrupter 16, 17, 18 could be omitted and the current generated 45 upon the war ship making contact with the copper cable of the barrier and with a buoy could be used for directly operating the fuze 12.

In order to remove a barrier (Fig. 5), wooden 50 boats will be used to approach the barrier and the buoys will be seized by means of grapnels. The buoys 3 carry preferably cables 28 connected to hooks 29 which can slide along the cables 2. When the barrier is to be removed, the cables 28 55 are detached from the buoys 3 and connected to chains 28a which are lowered from the boats to lower the hooks 29 until these engage in rings 30 carried by the foundation blocks 1, so that these blocks can be raised.

A further embodiment of the invention is shown 60 in Fig. 6, in the moment the barrier being broken by a submarine B. The ship pulls the three buoys 31 attached to a copper cable 32 along with her. The buoys 31 are sounding buoys and when the walls of the buoys make contact with the hull of 65 the submarine an electric current will be generated by the cell constituted by the iron of the hull, the sea water and the copper cable, which current will operate the sounding devices of the buoys; it is then possible to follow the further 70 course of the submarine, by following the sound emitted by the buoys taken along with the ship.

Each of the buoys 33 comprises a mechanical 75 device which, when the barrier is broken, closes an electric circuit including the battery 35 and a sounding device 35a of a known type. Such

mechanical devices are well known and are not represented. When a plurality of barriers, such as represented in Fig. 6, are placed in a certain region in the sea, and the sounding devices of two adjacent buoys 33 are operated, it will be known, 5 that the barrier had been broken between these two buoys. Such sounding buoys 33 could be naturally also be used together with buoys 31 which would contain an explosive charge.

Figs. 8 and 9 show a third form of a submarine 10 barrier in the moment when it is placed into the sea from a boat C, for example in order to constitute a defense means against a pursuing war ship. This embodiment comprises two ordinary floating buoys 38 to which are attached three explosive or sounding buoys 36 interconnected by a copper cable 37. Each buoy 38 is connected to a weight in the form of a roller 39, by means of a cable 40. This cable is wound many times around the roller 39 and a locking device prevents uncoiling of the cable. When the barrier is thrown into the water, it sinks first owing to the action of the weights 39. When it has reached a depth of from 25 to 30 feet, a hydrostatic device carried by the buoys 38 is actuated by the pressure 25 of the sea water and releases the locking device for the cable 40 which is uncoiled so that the weights alone continue to sink until they reach the ground, while the buoys 38 stay in place. The locking device for the cable 40 and 30 the hydrostatically operated means for releasing the cable being well known in the art, are not illustrated.

Figure 10 shows a modification of a connecting means between the explosive or sounding buoys. 35 The cable 5 is constituted by a cord carrying a number of small copper balls 41. An insulated conductor 42 leads from each ball into the interior of an explosive or sounding buoy. When the iron hull of a ship makes contact with the 40 copper balls, an electric cell is formed by the hull, the copper balls and the sea water. Connections in the interior of the buoy permit to connect the number of cells so formed in series or in parallel, 45 so that a sufficiently strong current will be generated, without requiring any relay and auxiliary battery, for actuating the means of defense in the buoys.

I claim:

1. A submarine barrier comprising a plurality of buoys, anchoring means for holding said buoys submerged, pulleys carried by said buoys, a cable extending between two adjacent buoys and passing over said pulleys, explosive buoys connected to said cable, and an antenna electrically connecting said explosive buoys and which when submerged in sea water has a different electrical potential from that of a ship's hull, said cable, said explosive buoys and said antenna forming together a loop-shaped barrier maintained by said pulleys between adjacent anchored buoys. 55

2. A submarine barrier comprising two spaced anchored floating buoys, electrically operated sounding apparatus enclosed in said buoys, pulleys carried by said buoys, a relatively weak cable passing over the pulleys to extend between the two anchored buoys, a plurality of explosive buoys connected to said cable, an antenna connected to said explosive buoys, said antenna being of a metal which when submerged in sea water has a different electrical potential from the metal of a ship's hull, said cable, said explosive buoys and said antenna forming together a loop-shaped 70 75

barrier maintained by said pulleys between the two anchored buoys.

3. A submarine barrier comprising a submerged cable forming a loop, mooring means for holding the loop submerged, means on said mooring means passing through the loop for loosely attaching the loop to the mooring means, a plurality of buoys connected to the cable to hold the loop extended in a substantially vertical plane and to provide the loop with a substantially horizontally extending upper loop section and with a lower loop section, said lower loop section being formed as ripping line whereby upon a ship running against said upper horizontally extending loop section the loop is tensioned until the lower section rips and the cable will be disconnected as a whole from the mooring means.

4. A submarine barrier comprising two spaced

anchored floating buoys, pulleys carried by said buoys, a cable extending between the two buoys and passing over said pulleys, explosive buoys connected to said cable, an antenna electrically connecting said explosive buoys and which when submerged in sea water has a different electrical potential from that of a ship's hull, said cable, said explosive buoys and said antenna forming together a loop-shaped barrier carried by said pulleys, and an additional buoy electrically connected to said antenna and having a buoyancy different from that of said explosive buoys, said additional buoy bearing on said cable to maintain the loop-shaped barrier extended in a substantially vertical plane between the two anchored buoys.
